INTELLIGENCE TRANSMISSION

Alda V. Bedford, Collingswood, N. J., assignor to
 Radio Corporation of America, a corporation of
 Delaware

Application April 8, 1933, Serial No. 665,072

16 Claims. (Cl. 178—6)

The present invention relates broadly to television systems and it is directed particularly to television systems wherein the pictorial action is viewed simultaneously with the production of 5 audible effects which are coordinated with the visual action taking place at the transmitter point.

It has, in general, been found in connection with any type of image viewing system, whether 10 it be motion pictures or television, that the action portrayed in the form of a light, electro-optical or other type of image is made considerably more realistic if the visible indications are accompanied by audible indications. It is with 15 the thought in mind that the efficiency, commercial utility, and interest in the system is considerably increased by the provision of means whereby the combined sound and image representations may be obtained that this invention has been developed.

20 Of course, it is quite obvious that these features may, in a broad and general sense, be realizable with the now existing systems if recourse can be had to several independent transmitters and several independent wave lengths or frequency bands are assigned for the purpose of 25 transmission of these intelligence signals. Such a system would, however, require and demand considerably greater space in the ether than a system of the type which is here being proposed.

30 Further, systems of the type wherein two distinct frequency bands, and, therefore two separate transmitters, are needed are not, of course, efficient since they require not only separate amplifying systems for the sound and picture signals but also require separately generated carrier frequencies and independent means for modulating these separate carrier frequencies. In addition, there is a great loss of available time 35 for transmitting the signals and especially the picture signals on apparatus of this type because where a cathode ray device or other type of electronic device is used as either the image transmitting instrumentality or as the image 40 reproducing or reconstructing device, provision should be made for the so-called uni-lateral scanning. By uni-lateral scanning is meant scanning action taking place always in one direction, that is, for example, always from left 45 to right on a viewing area. So arranged, it is quite obvious that in a system using a cathode ray tube as the image reconstructing device, for example, so that an electron pencil causes the electro-optical effects, the electron pencil must 50 move, for example, from left to right at a rela-

tively slow rate, or from right to left, that is, the return line, at a relatively faster rate, in order that the loss in time of actual intelligence transmission be reduced to a minimum.

5 According to one suitable form of transmission these rates may be of any order from six to one to ten to one, for example. One suitable ratio of the ray motion in the two directions is such that the slow motion period of ray traversal occupies relatively 90% of the complete scanning cycle necessary to produce one complete elemental strip or line of the constructed image subject, and then the rapid motion of the ray in the reverse direction occurs within a 10% period of the scanning cycle.

10 If now the ratio of nine to one, above suggested, is to be maintained, it can be seen that during the return line period of 10% there is really no useful transmission being carried out. If it is further assumed that the frequency band necessary to transmit a picture of the desired detail is, say, somewhat in excess of one megacycle which, for example, would be required that the subject divided for scanning and analyzing 15 purposes into slightly more than 300 distinct lines or elemental strips, and each elemental strip or line comprising 300 or more independent and distinct elemental areas where the repetition frequency is twenty-four complete image reproductions per second.

20 According to the above suggested conditions, only $\frac{1}{9}$ of the selected frequency band can be utilized to produce an electro-optical image effect with the above suggested detail. If the subject is assumed to be divided into 300 distinct 25 elemental strips or lines and 24 complete images per second are being transmitted it is apparent that the intelligence representing each elemental strip must be transmitted during $\frac{1}{9}$ ths of 1/7200ths of a second and that during the remaining 1/72,000ths second there will be no useful image transmission, the result is that there 30 is a loss of somewhat in excess of 100,000 cycles in the frequency band for this type of transmission. Of course, such a loss means that the load upon the transmitter does not remain constant or substantially constant and that a considerable portion 35 of the available frequency band cannot, in effect, be utilized.

40 It is one of the objects of this invention to provide ways and means by which this period of what might be termed "lost energy" transmission may be utilized. It is, therefore, proposed to transmit on the television carrier frequency during 45 the time intervals between the successive 50 55

transmission of intelligence effects representing the values of light and shadow for each elemental strip of the scanned subject, additional signals to represent the sound which occurred 5 during the transmission of the image signals representing the elemental strip just previously scanned. According to this form of the invention, the load on the transmitter will for $\frac{1}{6}$ ths of the time be a load determined by the image 10 signals and during the remaining $\frac{5}{6}$ th of the time, disregarding for the time being synchronizing signals, a load due to sound signals accompanying the image signals.

It has already been proposed in transmitting 15 television image signals to follow the image signals representative of each elemental strip of the subject by one or more synchronizing impulses. At the various points of reception of the transmitted image these auxiliary signals serve to 20 synchronize and coordinate in space relationship the reproduced electro-optical effects representative of the subject located at the point of transmission. In this way a portion of the time loss due to the reversal of the scanning path has 25 been compensated but, nevertheless, the time required to transmit the synchronizing signals is only relatively short compared to the total return line period or, in other words, the time required for the cathode ray pencil to return to its 30 original starting position.

In the preferred forms of cathode ray television apparatus now in use the position control of the cathode ray pencil is provided by suitably arranged deflecting circuits operating under the 35 control of energy having a wave formation which changes along a saw-tooth path. Such a wave formation can be produced through the use of relaxation oscillators, dynatron oscillators, grid-controlled oscillators or the like so that the output 40 voltage or current varies according to a saw-tooth pattern, by which is meant that there is a change in the intensity of the output energy serving as the control current or the controlling voltage for the tube ray deflection system from 45 minimum to maximum in one direction at a very slow rate, and in the other direction at a very rapid rate or vice versa. According to the above suggested arrangement the slow change period 50 will occupy $\frac{1}{6}$ ths of the scanning cycle for one line or elemental strip of the subject and the rapidly changing portion will occupy the remaining $\frac{5}{6}$ th of the scanning cycle for each elemental strip.

Suppose now that the line scanning frequency 55 is of the order of 4,800 to approximately 8,000 cycles per second, which, for example, would occur where the subject is divided into a number of elemental strips varying between 200 and 330. It can be seen that this frequency is not quite 60 sufficient for proper sound modulation impulses because the impulse carrier is not sufficient for high quality. However, two or three times the line frequency would be satisfactory because then sufficient of the higher frequencies to obtain 65 good reproduction would be present. Therefore, by suitable arrangements, a carrier frequency for sound which is two or three times the line scanning frequency can conveniently be generated by means of any of the types of oscillators above suggested for synchronizing purposes and serve as the auxiliary carriers which 70 can then be sound modulated.

According to the present invention, it is proposed to produce and select during the time 75 period of scanning each elemental strip of the

subject, certain portions of the sound occurring and then also to select a certain portion of the sound actually occurring during the so-called return line period. If, now, it is possible to select during the picture scanning period one distinct portion or "slice" of sound and another distinct portion or "slice" during the return line period, and if it is possible to delay the sound first selected during the picture scanning period until a time period just immediately prior to the time 10 period of actual occurrence of sound selected during the return line period, it can be seen that these two sounds can then be transmitted to follow the picture and synchronizing signal indications. These sound signals then can be 15 caused to control or modulate the television transmitter during the return line period.

To provide for operating this arrangement, it is necessary then to arrange at the receiving end 20 of the system a suitable means by which the sound signals actually occurring during the return line period are delayed in reproduction by a time period corresponding to the delay period at which the sound originating at the point of transmission during the picture scanning period is transmitted. 25 The proper relationship between both sounds will then be maintained except that both sounds have been delayed in time relationship by fixed and equal amounts. From such an arrangement it can be seen that by selecting as few as two 30 distinct "slices" or portions of sound the sound signals selected will each have an amplitude corresponding to the amplitude of the sound actually present. By plotting graphically these independent sound signals the resulting curve obtained by the differences in the sound signals from zero intensity will be an envelope corresponding exactly to the sound actually present in the first instance. Thus, it has been proven and established that to reproduce sound it is not 35 necessary that all of the sound actually existent should be transmitted but only just sufficient sound to provide enough points of plotting in order that the sound envelope may be determined. This relationship may be, for example, as little as 40 5% of the sound actually existing and due to the fact that a suitable filter in the receiver so smooths out the sound by the points represented so that there is reconstructed the envelope of the various points of varying amplitude and the reproduced sounds will be, so far as the listener is concerned, exactly the same as if all of the originally produced sound were actually present.

Therefore, it is one of the objects of my invention to provide ways and means by which it is 55 possible to transmit on a single carrier frequency, signals representing picture shade values, synchronizing impulses and sound indications.

Another object of the invention is to provide ways and means by which a substantial period of 60 the time available may be used for transmitting picture signals and in which a small portion of the time period available may be utilized for transmitting synchronizing and sound signals.

Another object of the invention is to provide 65 ways and means by which picture signals may be transmitted in their entirety and sound signals which are later to be reconstructed into the total sound available may be transmitted in minute proportions to the total sound signals available.

Still a further object of the invention is to provide ways and means by which certain predetermined differential sections or portions or "slices" of the total sound energy available may be selected and used to control the transmitter. 70 75

At the receiving points of the system certain portions of the total energy transmitted are suitably converted into a series of sound signals which, so far as the observer is concerned, have the same or substantially the same qualities and properties as the complete train of sound signals existing at the point of transmission. Such discrete "strips", "slices" or portions of the total energy may be further identified as including a differential segment of the area beneath the curve representing the envelope of the total sound available. In other words, what is really transmitted may be considered as a derivative of the band frequency wherein by the term derivative is meant index portion, a derived curve or any other form of signal which is derived from and whose value is determined by the characteristics of the original frequency. Of course, it will be apparent in this connection also that the original sound frequencies can be passed through any desired type of distorting device to produce and provide suitable other forms of derivatives. Such devices may be, for example, frequency multipliers and the like.

Other objects and advantages of the invention are to provide ways and means by which a plurality of different types of signals may be transmitted from a single transmitter over any appropriate connecting channel, such as a wire line or radio channel, to points of reception and provide at the receiving points the effect of continuity of both forms of message signals at the various points of reception irrespective of the actual interruption of each type of transmission for predetermined time periods at the point of transmission.

Other and further objects of the invention are, of course, to provide a system for transmitting sound and image signals wherein use is made of the time interval between successive scanning lines, assuming the system to be applied specifically to television apparatus, to receive and store up the essential information which in the receiving device is effectively released after certain fixed delay periods and then used to reconstruct the signal which the transmitted information contained. In this connection it may be noted that the period within which the transmission of picture signals is described could be used, where desired, to contain other sound signals instead of picture signals so that this system as defined by the present disclosure could be used as a means for transmitting multiple sound signals of different subject matter over a single radio or other communication channel.

Other objects of the invention are to provide a system for combined visual and audible signals which is relatively simple in its construction and arrangement of parts; easy to operate; capable of being installed in existing apparatus with a minimum of inconvenience and expense; and which reduces the expense of transmitting combined sight and sound signals by avoiding the necessity of utilizing separate transmitters, modulators, carrier frequency generators and the like for the separate types of transmission signals.

Still other and further objects of the invention will become apparent from a consideration of the following specification and claims in connection with the accompanying drawings illustrating one preferred form of my invention, wherein:

Fig. 1 illustrates conventionally and in block diagram formation suitable arrangements for transmitting and receiving apparatus;

Fig. 2 illustrates a portion of the transmitter end of the system;

Fig. 3 illustrates the relationship between picture, synchronizing and sound signals so far as time separation and division is concerned;

Fig. 4 illustrates conventionally various curves designated as *a* through *i* inclusive to show and illustrate various control or signal wave formations at the transmitter;

Fig. 5 illustrates diagrammatically one form of receiver apparatus; and

Fig. 6 illustrates by curves *j* through *r* inclusive diagrammatically the wave formations existing in the receiver in contrast to the wave forms found at the transmitter.

If reference is now made to the accompanying drawings for an understanding of the operation of this invention it may be assumed that television transmission is carried on according to well known and established principles of operation. For example, the television transmission may be carried out in accordance with the prior teachings of V. K. Zworykin as expressed, for example, in copending application Serial No. 574,772, filed November 13, 1931, assigned to Radio Corporation of America, except that no reference need be made to a particular color system and the application referred to is mentioned solely because of the fact that it illustrates one suitable form of cathode ray image scanning device. It is also to be understood that any form of mechanical scanning system may be used for producing the image signals provided that there is provided between the production of the series of the electrical signals representing successive lines or elemental strips of the subject of which the image is being produced a slight time separation of the order of $\frac{1}{6}$ th or less of the scanning time period required to transmit a single elemental strip or line of the subject.

If, for example, it is assumed that the subject being analyzed is scanned over its entire area at a repetition rate of 24 cycles per second, this being the customary film speed of standard motion picture film, and if it is assumed that each film frame is divided into a sufficient number of elemental strips that the product of the individual elemental strips and the image scanning rate per second is of the order of approximately 7000, it can be seen that the entire time required to scan each elemental strip of the subject will be of the order of 1/7000th of a second. Since all of this 1/7000th of a second time period cannot actually be used to transmit signal indications representative of light and shadow on each successive elemental area in a television system involving the use of cathode ray devices for scanning or reproducing the image, for example, due to the fact that wherever a cathode ray tube is used as the image scanning and/or reconstructing device time must be allowed for the "return line" period of the ray. The actual time allowed for the transmission of image signals per scanning cycle is of the order of 1/8000th of a second with the difference between the rate of the scanning cycle 1/7000th of a second) and the time used for actual transmission being provided for the so-called "return line" period.

So arranged, the television scanning device is operated to test or analyze the varying intensities of light and shadow on each elemental area of a subject. If it is assumed that the device is a cathode ray tube of the general type disclosed by Zworykin and others this tube may operate under the control of the horizontal synchronizing

signal source 3 and the vertical synchronizing or framing signal source 5 each of which preferably generates a saw-tooth wave form output and which is adapted to control the deflecting fields serving to control the motion or deflection of the cathode pencil within the television scanning device 1. So arranged, the horizontal frequency may have a frequency of the order of 7000 cycles and the vertical synchronizing frequency may have a frequency of the order of 24 cycles per second.

Each of these sources 3 and 5 serves to control and bias to cut-off at predetermined times the television signal amplifier 7 which has its input circuit supplied with energy from the television scanner 1 so that when the amplifier is operative the signals produced from the television scanner are suitably amplified but at other times there will be no output from the amplifier. By this arrangement the television amplifier is so arranged that during the return line or rapidly changing period of the saw-tooth cycle the output is negative.

The output energy from the television amplifier 1 is then supplied by way of appropriate conductors to the combined signal amplifier 9, which also serves to amplify the pulses of energy resulting from the horizontal synchronizing source 3 and the vertical synchronizing source 5, which signals have previously been amplified by means of the amplifier 10 so that they are 180° out of phase with respect to the picture signals. Where desired, the energy following each series of signals representative of the variations in light and shadow and serving to represent the synchronizing signals may be produced by the scanning element itself as disclosed, for example, by copending application of A. W. Vance, Serial No. 544,959, filed June 17, 1931, assigned to Radio Corporation of America.

The speech or audible signals which accompany the pictorial representations transmitted by the television scanner 1 are caused to influence the sound signal transmitter 11 and are then supplied to the sound amplifier 13 whose output energy is directed through a sound delay unit 15 of which the purpose will hereinafter be explained. The output from the sound delay unit 15 is then supplied to a sound amplifier device 17 to which in turn is supplied energy from a correcting impulse source 19 of which the purpose will also hereinafter be explained. The sound signals thus selected are then caused to be passed to the combined signal amplifier 9 to which it has been explained above the picture and synchronizing signals are supplied.

The output energy from the combined signal amplifier representing sound, picture and synchronizing signals is directed to the modulator 21 to which energy from the carrier frequency oscillator 23 is supplied and the modulated carrier frequency is suitably amplified by the amplifier 25 and transmitted by way of the connecting channel 27 herein indicated as a radio channel, although a wire connecting link is equally suitable, to a receiving point where this energy is amplified and detected in well known manner by the receiving amplifier and detector 29.

As the received energy includes sound, synchronizing and picture signals, it is desirable that these signals be appropriately separated one from the other. The synchronizing signals are separated from the picture impulse signals in well known manner, which may be either by a wave form selection or by an amplitude selection.

These separated signals representing the picture and the synchronizing impulses are supplied to the picture signal amplifier 35 and to the vertical and horizontal synchronizing control devices 31 and 33, respectively.

As is now well known in the art, vertical synchronizing signals which may be appropriately controlled from the transmitted signals cause the scanning cycle to be repeated at a rate of 24 complete image representations per second, for example, and are effective for control during the time interval between the completion of scanning of the last or lowermost elemental strip of the subject, for example, and the start or uppermost elemental strip of the next succeeding elemental strip of the subject. The vertical synchronizing signal is adapted not only to control the position at which the electro-optical effects in the image reconstructing device 37 are produced, but also serves to render the picture signal amplifier or the image reconstructing device, or both, as desired, inoperative during this so-called "return line" period. Similarly, the horizontal synchronizing system which controls the line scanning rate is adapted to render either the picture signal amplifier or the image reconstructing device inoperative during the "return line" period between the reproduction of successive elemental strips. This type of control is well known and does not constitute a part of the present invention except insofar as it cooperates with the general combination of the various other elements to include new and novel subject matter.

In order to receive and reproduce the sound signals special arrangements must be made in the receiver. These features will be described later in this disclosure after making further description of the transmitter end of the system.

If reference is now made to Fig. 3 illustrating the relationship between the instantaneous position of the cathode ray pencil and the time, it can be seen that during the time period T1 the deflection of the ray is increasing from a minimum to a maximum and during the time period T2 the cathode ray pencil is being returned from a position of maximum deflection to a position of minimum deflection, during which period this change in position is occurring very rapidly. It is during this time period T2 that no useful picture signals are being transmitted and, consequently, if the time periods T1 plus T2 are of the order of $\frac{1}{7000}$ th of a second and the frequency band required for transmission is of the order of 1 mega-cycle, then during the period T2 there is transmitted substantially 100 kc. of energy which normally would not be put to any useful purpose. Therefore, it is proposed to transmit during the time period T2 the representations of the sound accompanying the picture action which is to be portrayed as occurring within the time period T1.

According to the present suggested scheme it is proposed to select during the time period T1 an elemental strip or segment of sound, generally designated as *a*, which occurs substantially midway between the positions of zero and maximum deflection and to select a second elemental segment or strip during the time period T2, which has been designated as *b*. However, it is impossible to transmit the sound signal *a* at the point in time where it is actually produced since it is at this time that the picture signals are being transmitted. Therefore, in order to bring the sound signal represented by the strip *a* within the idle period of the transmitter this sound signal

may be delayed through an appropriate form of delay network to be described in connection with Fig. 2 so that it assumes a position in time designated in dotted lines as a' , under which conditions both sound signals a and b will follow each other at a predetermined time in the scanning cycle.

One suitable form of apparatus for carrying out this invention, neglecting for the time being the synchronizing signals which will occur and be transmitted in the space period between the position of maximum deflection of the cathode ray pencil of the scanning device, designated as time period B, and the time at which the sound signal a' is to be transmitted, as shown by Fig. 3 for example. According to the system shown by Fig. 2 there is shown an arrangement which is intended to combine substantially the sound delay circuit, the sound amplifier, and the impulse signal source, designated as 15, 17 and 19 respectively by Fig. 1, and to supply the resulting output signals to the combined signal amplifier 9 of Fig. 1. The amplified signals from the sound signal amplifier 13 are impressed upon the terminal 41 while suitable impulse signals from the source 19 are supplied to the terminal 43. The impulse signals may be generated by any desired form of apparatus such, for example, as the horizontal synchronizing signal source arranged to trigger at predetermined time periods a square wave amplifier device, for example, or the signals may originate from a rotating scanning disk provided with suitable apertures through which light from a light source is directed to a photoelectric tube and amplifier, where the disk rotates at a speed commensurate with the frequency of the impulse desired, or the signals may be produced and generated by any other suitable form of arrangement. This impulse source is, of course, synchronous with the picture scanner deflecting circuits.

According to the present invention this correcting impulse signal in the form of a synchronizing impulse, as shown by Fig. 4a, which has a frequency of the order of 7000 cycles and is preferably an impulse wave of the general form indicated. It is to be assumed for the purpose of understanding this invention that this signal is so timed that one impulse occurs at the end of each scanning line of the picture, that is, after each scanning period A B (see Fig. 3). The impulse so produced is applied to the terminal point 43 and is then passed along the artificial line or impulse delay network 45 comprising a plurality of series inductance and shunt capacity elements 47 and 49. This artificial line acts to delay the impulse so that the wave at the top of the delay line reaching the point 50 is delayed .05T₁ seconds, where T₁ equals 1/7000th of a second as has been shown by the curve illustrated in Fig. 4b. This delayed impulse will, for convenience of description, herein be termed the "odd" impulse. The wave appearing across the terminating resistance 51 of this artificial line 45 is the result of the synchronizing impulse of Fig. 4a being delayed an additional .05T₁ seconds. This impulse may, for example, be termed for convenience of reference the "even" impulse, and is shown in Fig. 4c.

The wave form illustrated for example by curve d of Fig. 4 is a part of the sound wave applied from the sound amplifier 13 to the input terminal 41 of the sound delay unit 15. A part of this sound energy is impressed by way of a conductor 75 and suitable coupling capacity 53 upon the screen

electrode 57 of the screen grid tube 55. This tube 55 is normally biased to cut-off by its control grid 59 and passes no plate current except at time periods when the "even" impulses arrive from the artificial line 45 and are applied to the control electrode 59 of the screen grid tube 55 by way of a capacity 61 connected with the end of the artificial line 45. The amplitude of the impulses of current that flow is proportional to the instantaneous sound wave voltage and hence the voltage across the output resistor 63 during the time period a' and b of the time period T₂ (see Fig. 3) is representative of a sound signal and are negative. These modulated impulses are shown by Fig. 4e with the polarity changed to positive and altered scale to show how the height of the impulses is controlled by the sound wave applied to the input terminal.

In a similar manner the "odd" impulses of the curve of Fig. 4 are supplied to the tube 65 and are controlled by the delayed sound wave signals (shown by Fig. 4f) which are also applied to the tube 65. These delayed sound wave impulses appear across the terminating resistor 67 of the delay line 69 formed from a combination of series inductance and shunt capacity elements 71 and 73 which terminates at the resistor 67. The delay network 69 has a time delay period equal to approximately 0.5T₁.

The modulated impulses resulting from the delayed sound signals are shown graphically by Fig. 4g. It should be noted particularly in this connection that the delayed sound wave appearing across the resistor 67 at the end of the artificial line 69, which signal modulates the "odd" impulse from the artificial or delay line 45, is really that part of the sound which originally occurs first in time and hence must be made to reach the loudspeaker or sound reproducer first as regards time in the final receiver. The time delay in the artificial line 69 is substantially equal to one-half the time period T₁ so that the "odd" impulses are modulated by the portions of the sound belonging midway between the parts modulating the "even" impulses.

The grid of the tube 75 is excited by the simple undelayed synchronizing impulses shown by the curve 4a without modulating. The grid of the tube 77 is excited by the picture signal originating from the picture signal amplifier 7, which is such a curve as the dotted line curve shown by Fig. 4i, which is arranged to have a fixed value approximately zero during the time of the three impulses included as a part of the curve 4h to indicate synchronizing signals and speech or sound signals. The plate resistor 63 above mentioned may be common for all tubes 75, 65, 57 and 77 and hence serves to combine the waves shown by Figs. 4a, 4e, 4g and 4i, as shown. The amplified output energy from the combined signal amplifier 9 will then be a signal which contains the information for reconstructing both picture and sound, as can be seen more clearly from Fig. 6j, and this signal together with the included synchronizing impulse is then transmitted by a single radio channel.

At the receiver end of the system signals may be received in any desired and preferred manner. For example, the type of receiver may be, in the broadest sense, of the general form suggested and disclosed by copending application of J. Weinberg, T. A. Smith and G. Rodman, Serial No. 360,065, filed May 3, 1929 or in accordance with the disclosure of copending application of W. L. Carlson, Serial No. 583,193, filed December 75

26, 1931 which applications are assigned to Radio Corporation of America. So arranged, the signals received are conventionally shown as being separated in and by the receiving amplifier 29 5 and then supplied to the vertical synchronizing signal control device, the horizontal synchronizing signal control device and the picture signal amplifier 31, 33 and 35, respectively. The sound signals and one of the synchronizing impulses 10 (also the picture signal) are then arranged so as to be supplied to the synchronizing impulse selector 11, the even impulse selector 13 and the odd impulse selector 15, each of which arrangements is more particularly shown in its preferred form by Fig. 5 of the accompanying drawings.

If reference is now made to Fig. 5 a portion of the output energy from the receiver amplifier 29 20 may be considered as being supplied to the terminal point 17. This output will be in the form of a voltage wave such as that shown by Fig. 6j which, it will be noted, is essentially the same as the output signal appearing across the resistor 63 of Fig. 2, and the wave form, it will 25 be noted, corresponds substantially to the combined wave forms of Figs. 4h and 4i.

So impressed upon the terminal 17 the several impulses must be separated from one another and from the picture portion of the signal. The synchronizing impulse is preferably maintained greater in amplitude than any other impulse or picture signal and due to this fact is selected by the tube 19 which is biased so strongly negative that plate current is adapted to flow only during 35 the synchronizing impulse period. The variation in the amplitude of the synchronizing signal compared to other signals has already been disclosed and set forth by the above named application of A. W. Vance. The selected impulse is 40 then amplified and reversed in polarity by means of the amplifying tube 81 which has its input circuit appropriately connected with the output from tube 19 by way of the capacity coupling 83. It can be appreciated from what has been above 45 stated that the output voltage wave from the tube 81 will be of the general form shown by the curve of Fig. 6k. This signal, identified as the selected synchronizing impulse, is then impressed upon the signal delay network, generally designated as 85, which comprises the combination of series inductance and the shunt capacity elements 87 and 89 and a terminating resistor 105. The delayed signal impulses, represented by the curves of Figs. 6l and 6n, due to the delay period 55 of the delay line 85 indicated by the drawings, have been delayed by the proper amount of time to coincide with the sound modulated sound impulses yet to be selected. The impulse output from the portion of the delay line 85 between the 60 connection to the output of the tube 81 and the point 91 designated by the arrows as including a delay period of $.05T_1$ are selected at the point 91 by means of a conductor 93 connected thereto and then impressed upon the control grid of tube 65 95 by way of a capacity coupling 97 connecting therewith. This tube 95 is normally so biased that no plate current flows except during the time intervals during which an impulse is supplied thereto by reason of a signal being passed by the 70 delay network 85.

Also, since the complete picture, sound and synchronizing signal is impressed upon the screen grid electrode 99 by way of the capacity connection 101 made to the terminal point 17 the plate 75 current impulse is controlled in amplitude by the

"odd" sound modulated impulse which occurs at the same time. In this manner it may be said that the "odd" sound impulse signal is selected. This selection and the resulting output is represented, for example, by the curve designated as Fig. 6m.

Similarly, the further delayed impulse curve shown as Fig. 6n acts to control the operation of the tube 103 to select the "even" impulse. This tube 103 is controlled by way of the signal supplied thereto from the end of the delay line 85, which appears across the resistor 105, through a capacity coupling connection 107 connecting the end of the line with a control electrode of the tube so as to apply the signal to the control grid 15 109 in a manner similar to that explained in connection with tube 95. The signal impressed upon the input terminal 11 is supplied to the screen grid electrode 111 of the tube 103 by way of the capacity coupling 113 and due to the fact 20 that the impulse serving to change the operating characteristic of the tube 103 from a point where it is biased below cut-off to an operative position is delayed in time by a time delay period equal to $.05T_1$ later than the signal serving to control 25 the tube 95 the "even" sound impulse characteristics, shown by the curve of Fig. 6o, are selected.

As has already been mentioned in this discussion in connection with the transmitter, the "odd" sound impulse should reach the sound reproducing device 139 first in the point of time of reproduction and, therefore, in the receiver system the "even" impulse must be delayed in time to a still further degree than has thus far been explained. Such a delay period has been illustrated graphically by the curve shown by Fig. 6p.

Such a further time delay of the "even" impulse may be accomplished by means of a suitable delay line, generally designated 115, which also comprises suitable shunt capacity and series inductance elements 117 and 119 which are connected with the output circuit of the tube 103 by way of a coupling condenser 121. This delay line 115 terminates in the usual terminating resistor 123 and has a delay period equal approximately 45 to $.5T_1$, which, it will be recalled, is the same time delay period as the delay network 69 shown and described in connection with Fig. 2. The signal appearing across the resistor 123 of the delay network 115 is then supplied through the 50 condenser 125 by way of a conductor 127 and a resistor 129 to a low pass filter 131 which is adapted to cut-off at approximately 7000 cycles, that is, the assumed line scanning frequency, and above per second, although, of course, it is to be 55 understood that this cut-off point may be varied within wide limits as desired. The output energy from the tube 95 is also supplied in common with the output of the delay line 115 to this same low 60 pass filter 131 by way of the capacity coupling 133 and resistor 135 which connects to the end of the resistor 129 leading to the filter 131.

The combined curve resulting from the signals indicated in their general wave form by Figs. 6m and 6p has been conventionally shown by Fig. 6r. 65 This wave formation contains the information for reconstructing the original sound wave shown by Fig. 6q and is obtained by passing this wave formation through the low pass filter 131 to remove the assumed 7000 cycle scanning frequency 70 component and all other higher frequencies. The output voltage from the filter 131 is amplified still further, if desired, by way of an amplifier 137 and then supplied to a suitable sound reproducing device 139 connected to the output terminals 141. 75

It is thus seen that as images of a subject are being reconstructed upon the image reconstructing device 37 the sound which accompanied the visual action causing the images is simultaneously reproduced by the sound reproducer 139. In analyzing this method of transmitting a sound wave it may be considered, in accordance with the above explanation, that at the transmitter single point observations of the sound wave are taken at $\frac{1}{4000}$ ths of a second intervals and are transmitted as such at the receiver. These values are, in effect, replotted as points of varying amplitude on a curve so as to reconstruct electrically the original wave. Obviously, the more frequently these observations are taken the more variations in the sound wave may be ascertained or, in other words, the higher frequency sound may be transmitted. This is the primary reason why it is desirable to use, where possible, more than one impulse per line of picture scanning. Any additional impulses, however, make it necessary to provide more delay networks for delaying the impulses and additional provisions to segregate the various impulses into groups because the impulse cannot be transmitted at uniform time spacing without occurring during the picture scanning line instead of at the end of a picture scanning line as disclosed herein. It is, therefore, apparent that the method herein described could be used equally well for the transmission of three or more impulses per line of picture without departing from the spirit and scope of this disclosure. Also, it will be understood that any such additional impulses might be used for transmission of other information such as might be required for producing binaural effects, picture background control, or sound and picture volume control.

It should also be understood in the consideration of this invention that for convenience of illustration square-topped waves with vertical sides have been illustrated by the various curves. Such a shaped wave is substantially impossible to transmit and would, in practice, ordinarily be replaced by impulses with rounded corners and slightly sloping sides. In practicing this invention it will be understood that the spacing between the impulses may be decreased to some extent where desired. Therefore, the present illustration must be regarded as being of a rather conventional nature and serving only to indicate and set forth the principles upon which the present invention is based rather than as defining the invention in any concrete and limiting form.

In this connection it should be understood that wherever operating voltages have been described or illustrated, these are given merely as illustrative examples for the purpose of defining one form of the invention and that the invention is not limited to any particular operating voltages or values of the various circuit constants used, all of which may be varied within wide limits.

I claim:

1. The method of transmitting simultaneously occurring audible and visual signals upon a single carrier frequency which comprises generating a transmission carrier frequency, modulating the generated carrier by visual signals for a predetermined time period, interrupting the visual signal modulation for a minute time period compared to the modulating period, selecting during the visual signal modulating period a minute portion of the audible signal available and modulating the generated carrier frequency by the previously selected audible signal during periods of

interruption in visual signal modulation and for a time period corresponding to the selection period.

2. The method of communicating sight and sound signals which comprises alternately transmitting and interrupting the transmission of sight signals, selecting during a predetermined time period during which sight signals are transmitted minute portions of the total sound and transmitting during sight signal interruption and for the same predetermined time interval as included in selection the selected sound portions to produce at receptive points the effect of the entire intelligence available at the transmission point.

3. Method of transmitting sight and sound signals which comprises transmitting signals representing sight for a predetermined time period, interrupting the transmission subsequent to the production of sight signals representing a single line of the subject, limiting the interruption period to the order of one ninth that of the transmission period, selecting during the sight transmission period a minute portion of the total sound energy available, selecting during the sight signal interruption period a second minute portion of the total sound available, and transmitting during the sight signal-interruption-period both the selected minute portions of the sound energy available during both sight transmission and interruption periods.

4. The method of communication, comprising the steps of sequentially and cyclically transmitting line image signals, synchronizing signals, and at least a pair of sound signals, confining the time period of transmission of image signals to a time order of nine times the combined synchronizing and sound transmission time period, developing at least one of the sound signals during the period of image signal transmission, and delaying the sound signal developed during the image signal transmission period for a time period at least equal to the unexpired time portion allotted to image signal transmission.

5. The method of communication which comprises the steps of transmitting visual signals, cyclically interrupting the transmission of the visual signals for a time period small compared with the time period of transmission, developing a synchronizing signal, developing a sound signal during the transmission of the visual signal, developing a second sound signal during the period of interruption of the visual signal transmission, delaying the first developed sound signal, transmitting sequentially during the interruption period the developed synchronizing signal and the developed sound signals and controlling the sound transmission signals to transmit the same in the inverse order of the development of the sound signals.

6. The method of transmitting upon a single carrier frequency audible signals occurring simultaneously with a plurality of visual signals representing the light values upon successive elemental strips of a subject of which the image is desired which comprises generating a transmission carrier frequency, modulating the carrier by visual signals for a predetermined time period corresponding to the time required to scan a single elemental strip of the subject, interrupting the visual signal modulation for a time period short in duration with respect to the modulating period, selecting during the visual signal modulating period a minute portion of the total audible signal available, delaying the

selected audible signals for a time period substantially one-half the visual signal transmission period, and modulating the carrier by the time delayed audible signals during periods of interruption in visual signal modulation.

7. The method of transmitting a combined visual and audible series of signals which comprises producing for at least 60% of a selected unit time period a series of signals representing visual indications of successive strips of the subject, interrupting the visual signal control by the visual indications for the remaining portion of each unit time period, selecting at predetermined time during the period of image transmission discrete portions of the total sound energy accompanying the visual indications, delaying the effects of the selected sound energy for a time period corresponding substantially to the time equal to the difference of time of interruption of visual signals and the time of selection of the minute portion of sound energy, and transmitting during the periods of interruption of visual signals a series of independent signals representing the audible effects originally accompanying the previously transmitted visual signals.

8. The method of transmitting sound and image signals which comprises producing and transmitting a series of signals representative of the image, interrupting the transmission of image signals at the end of each line of the image, selecting a minute portion of total energy representative of sound produced during the scanning of a line of the image, delaying the sound impulse and transmitting the sound impulse during the period of interruption of the image signal.

9. In a system for transmitting picture signals representations accompanied by related sound, means for scanning a subject of which the image is desired along a series of substantially parallel paths produced under the control of a saw-tooth formation control signal, means for transmitting during a portion of a complete cycle of the controlling saw-tooth pattern control signal other signal representations representative of the varying lights and shadows on elemental areas of the subject, means for selecting during the time of transmission of image signal representations a predetermined portion of the total sound energy accompanying the picture representation, means for selecting during the periods of interruption of the transmission of picture line signals a second portion of the total available sound, means for delaying the first selected portion of sound energy for a predetermined time period, and means for transmitting after the predetermined time delay both selected sound signals during the interval between successive picture transmissions.

10. In a system for receiving combined image and sound signals transmitted sequentially and reconvert both signals into representations having the effect of continuity of reproduction, means for producing from the picture signal portion of the received energy electro-optical effects representative of the subject, means for selecting from the sound signals produced in the interval between successive lines of image signals indications representative of the desired sound, means for delaying at least one of the selected sound signals for a time period substantially greater than the time period during which sound signals are received, and means for reproducing the sound signals one at the natural time of reception and one at a delayed time of reception corresponding to the delay period to produce audible

effects representative of continuous sound production.

11. In a system for transmitting intelligence, means for selecting minute elements of the intelligence at substantially equal time intervals, means for delaying either the odd or even elements for a time period substantially equal to the time separating the successive elements, means for transmitting the undelayed element at the time it is selected, means for transmitting the delayed element accompanying the undelayed element substantially equal to the time separating the successive elements, means for transmitting the undelayed element at time it is selected, means for transmitting the delayed element accompanying the undelayed element continuous therewith, means for receiving the transmitted elements, means controlled in accordance with the cyclic rate of periods of transmission and reception of the selected elements for expanding the received elements in time relationship, and means for reproducing the time expanded signals to produce energy simulating the total intelligence available at the transmission point.

12. A system for transmitting and receiving combined visual and audible signals which comprises means for transmitting and interrupting the transmission of visual signals for time periods bearing ratios of the order of nine to one with respect to each other, means for selecting during the period of transmission and during the period of interruption of transmission of visual signals minute portions of the total sound energy available, means for delaying the signals resulting from the selection of the sound energy occurring during the period of visual transmission for a time corresponding substantially to the period of continuance of the visual transmission prior to its succeeding interruption, means for transmitting during the period of interruption of the visual transmission each of the selected sound signals sequentially, means for transmitting during the period of interruption of visual signal transmission a synchronizing signal to indicate the rate of repetition of the visual signal transmission, means for receiving the transmitted signals, means for reconstructing from the transmitted signals electro-optical effects synchronized in space position by the transmitted synchronizing impulses, means for separating the sound signals representations from the visual signal representations into independent groups of sound signal energy corresponding to the selected continuously transmitted sound signals, means for delaying one of the separated sound signals for a time period sufficient to produce the effect at the point of reception of two independent sound signals having the same time separation as the two selected signals at the point of transmission, and means controlled by the received synchronizing signal impulses for controlling the reproduction of the selected sound signal representations.

13. In a system for transmitting visual, sound and synchronizing signals over a common transmission network and wherein the picture is scanned during an elemental time period along a series of substantially parallel paths produced under the control of a saw-tooth pattern controlling electrical wave having a ratio of scanning to interruption of the order of nine to one during the unit scanning period for each elemental strip of the subject, means for producing during the longer portion of the elemental time period signals representing the varying values of light and shadow

- of the several elemental areas of the subject of which the image is desired, means for producing immediately subsequent to the production of the image signals a signal indicating the rate of repetition of production of image signal effects, means for selecting during the period of production of image signal effects a minute portion of the total sound energy accompanying the visual effects, means for selecting during the period of interruption of transmission of visual effects a second like time duration segmental portion of the total sound energy accompanying the visual effects, means for converting each of the selected segmental portions of sound into electrical impulses, 5 means for delaying the impulses representative of the sound occurring during the visual transmission for a time period sufficient to cause the resulting signals to occur during the period of interruption of the visual effects and at a time 10 period minutely separated from the selected sound effects occurring during the period of interruption of visual transmission, and means for transmitting all of the selected signals in such a relationship that the transmission is controlled 15 by visual signals, synchronizing signals and sound signals in sequence.
14. A system for receiving and reproducing sound and visual signals in which the sound signals are transmitted between the lines of visual signals received as modulations of a received carrier frequency which comprises means for converting the visual signal portion of the received modulated carrier frequency signals into electro-optical image effects, means for producing from the sound modulated portions of the received carrier frequency energy a plurality of independent 20 signals representative of sound accompanying the visual signals, means for delaying at least one of the independent sound signals for a time period such that the selected sound signals are substantially equally separated in time and so that one at least of the sound signals is reproduced during the time period of reproduction of visual effects, and a sound reproducing device for converting the sound signals into audible effects to accompany the visual effects. 25
15. A system for transmitting combined visual and audible signals which comprises means for transmitting and interrupting the transmission of visual signals line by line bearing ratios of transmission and interruption of the order of nine to one, means for selecting during the period of transmission and during the period of interruption of transmission of visual signals minute portions of the total sound energy available, means for delaying the signals resulting from the selection of the sound energy occurring during the period of visual transmission for a time period sufficient to cause both sound signals to occur in time relationship within a period of interruption of visual transmission, and means for transmitting each of the selected sound signals sequentially during the period of interruption of the visual transmission. 30
16. In a system for transmitting intelligence, means for selecting minute elements of the intelligence at substantially equal time intervals, means for delaying either the odd or even elements for a time period, and means for continuously transmitting each group of odd and even impulses in inverted order. 35
